UNITED STATES PATENT OFFICE.

ERNEST A. BOHLMAN, OF CHICAGO, ILLINOIS. ASSIGNOR TO KELLOGG SWITCHBOARD AND SUPPLY COMPANY, OF CHICAGO, ILLINOIS, A CORPORATION OF ILLINOIS.

KEY.

Application filed October 11, 1920. Serial No. 416,184.

To all whom it may concern:

Be it known that I, ERNEST A. BOHLMAN, a citizen of the United States, and residing at Chicago, in the county of Cook and State 5 of Illinois, have invented certain new and useful Improvements in Keys, of which the following is a description.

My invention relates to an operating key for selective party-line ringing and has to 10 do more particularly with that class of keys wherein the last key depressed remains in a partly depressed or indicating position by reason of its engagement with a mechanical latching device to indicate to the operator 15 which key was last operated.

An object of my invention is to provide an improved form of construction so as to insure the efficient operation of the key, and to provide a structure of few and simple 20 parts, easily assembled and easily accessible.

A feature of my invention is the provision of an improved plunger rod constructed without expensive machining operations, which provides a convenient 25 mounting space for the spring operating roller, and also so constructed as to prevent it from rotating in its guides without the use of extra parts for this purpose.

Another feature of my invention is the 30 means provided whereby the springs associated with the spring operating plunger are assembled units and conveniently secured to a mounting plate so that if a spring unit of a particular key plunger is in need of 35 repair or a different combination is desired, it may be replaced without disturbing any of the other spring units.

A further feature of my invention is the 40 novel construction of the latching plate in combination with the key plungers, which brings about a positive latching and unlatching of the key plungers and maintains the different actuating members of the key 45 in their various positions.

In well-known party-line ringing keys, a 50 plurality of reciprocating keys and a rocking two-way key are provided, the reciprocating keys being used for ringing purposes and the two-way rocking key for listening and ringing purposes. Keys of the 55 above type are constructed to indicate which one of the key plungers was last operated, but no indication is given when the rocking

key was last actuated for ringing purposes. Another feature of my invention, therefore, 55 is the provision of an arm associated with the rocking key which is operatively associated with the latching plate in such a way that when the rocking key is actuated for ringing purposes the latch plate is actuated 60 so as to release any off-normal key plunger to thus indicate to the operator that the rocking key was the last one operated.

My invention also includes other features and details which, together with the above, 65 will be more fully understood upon reference to the following detailed description taken in connection with the accompanying drawings, in which like reference characters in the several views denote like parts, and 70 in which—

Fig. 1 is a side elevation of the key structure of my invention;

Fig. 2 is a plan view of Fig. 1;

75

Fig. 3 is a right-end view of Fig. 1;

Fig. 4 is a reverse side elevation of Fig. 1;

Fig. 5 is a right-end view of Fig. 4;

Fig. 6 is a bottom view of Fig. 4;

Fig. 7 is a sectional view along the line 7—7 of Fig. 1, showing the key plunger in 80 its normal inoperated position;

Fig. 8 is a view similar to Fig. 7, but showing the key plunger in its fully depressed position;

Fig. 9 is a view similar to Fig. 7, but 85 showing the key plunger in its locking or indicating position;

Fig. 10 is a partial side elevation of the key showing the two-way rocking key in its listening position;

90

Fig. 11 is a view similar to Fig. 10, but showing the two-way rocking key in its ringing position;

Fig. 12 is a sectional view along the line 12—12 of Fig. 1, showing the two-way rock- 95 ing key in its normal position;

Fig. 13 is a sectional view along the line 13—13 of Fig. 11, showing the two-way rocking key in its ringing position and illustrating the arm associated with the rocking key, having moved the latching plate to the left to allow the restoration of a key plunger that is in indicating position;

100

Fig. 14 is an end view of the key with parts broken away to illustrate the position 105 of the latch plate when a key plunger is

in its fully depressed position, and its co-operating button which operates the end springs of the key;

Fig. 15 is a perspective view of the latch plate; and

Fig. 16 is a perspective view of the key plunger.

The combined key construction includes a plurality of ringing keys of the plunger type in association with a ringing and listening key of the lever or rocking type, all mounted compactly upon a frame. Each longitudinal movable key has three operating positions, a normal, a fully depressed and an intermediate position, the fully depressed position being the position in which the end springs common to the key plungers are actuated and the intermediate position being the ringing position and indicating position. A pivoted latch or catch plate operates with the key plungers in retaining them in their various operating positions. The rocking key cooperates with the latch plate to restore any operator's key plunger when the rocking key is actuated to its ringing position.

Referring now in detail to my invention as illustrated in the accompanying drawings, it comprises an escutcheon plate 2, and secured thereto by means of the screws 60 is an inverted U-shaped frame 3, upon which are mounted the operating parts of the key. The lower ends 4 and 5 of the inverted U-shaped frame 3 are connected by the spring supporting plate 6, which is secured to the ends 4 and 5 of the frame 3 by means of the screws 7, and a plunger guiding plate 8 is secured to the ends 4 and 5 by means of screws 9. The spring supporting plate 6 has secured to it a plurality of U-shaped members 10 by means of screws 11, and insulatingly mounted upon the members 10 are the spring contact members 12, 13 and 14. I have illustrated four key plungers, this being the usual number in the party-line key, and as the key plungers are all similar in construction, a description of one will suffice for a clear understanding of the key.

As shown in the drawing, the plunger rod P is made of a metal stamping and comprises an upper portion 15, an intermediate or body portion 16 and a lower portion 17. The upper portion 15 extends upward through suitable openings 18 and 19 in the plate 2 and frame 3, and the lower portion 17 enters a guide hole 20 in the angular portion 21 of the connecting plate 8. The plunger rod is made preferably flat, and the upper and lower portions 15 and 17 are rectangular in shape and pass through suitable rectangular orifices 18 and 19 in the plate 2 and frame 3, and a rectangular orifice 20 in the angular portion 21 of the connecting plate 8, to prevent the turning of the key plunger. An anti-friction roller 22 is rotatably secured to

the outer face of the body portion 16 of the plunger rod by means of a pivot screw 23 and is adapted to engage the spring 13 to move it from engagement with the spring 14 and press it into engagement with the spring 12. The plunger rod is also provided with a projection 24 integrally formed with the body portion 16 of the plunger rod P by means of a shearing operation and adapted to cooperate with the latch plate 25 for purposes as will be presently described.

Referring now to the latch plate 25 as clearly illustrated in Fig. 15, it is preferably stamped from a single sheet of metal and is secured to the legs 4 and 5 of the U-shaped frame 3, and for this purpose the latch plate 25 is provided on its opposite ends, adjacent to its lower edge, with projecting members or ears 26 and 27 adapted to lie flat against the inner faces of the legs 4 and 5, and is pivotally secured thereto by means of the pivot pins 28. Along the upper edge 29 of the latch plate 25 I provide a plurality of angular projecting members 30 integrally formed with the said latch plate 25 and which members 30 are adapted to engage the projections or tongues 24 of the plunger rods P when one of them is depressed to hold the said key in its indicating position.

The latch plate 25 is provided with rearwardly projecting members or tongues 31 which are formed integrally therewith by means of a shearing operation. Now, when a key plunger P is fully depressed, the tongue 24 on the plunger rod P engages the tongue 31 of the latch plate 25 and moves the said latch plate 25 outwardly to unlatch any key plunger P that may be in its indicating position, as will be more fully hereinafter described. Near its upper edge and at one end of the plate 25, I provide an integrally formed arm 32 extending at right angles to the face of the plate 25. A laterally projecting member 33 of suitable insulating material is secured to the arm 32 of the plate 25 by means of a screw 34 and is arranged to project through a slotted opening 35 in the leg 4 of the frame 3, and is adapted to engage a spring 36 of the end spring group ES to move the end springs to their alternate positions when a key plunger is depressed to its fully depressed position, as will be more fully hereinafter described. The end spring group ES comprises springs 36, 37, 38, 39, 40 and 41, which are suitably mounted upon an angular bracket 42, which bracket 42 is secured to the leg 4 of the frame 3 by means of the screws 43. The springs 36, 37, 38, etc., are insulatingly secured to the bracket 42 by means of the screws 44.

As previously indicated, the key structure includes a listening key lever L, which extends through a suitable opening in the

escutcheon 2. The key comprises a T-shaped frame 45 which is suitably fastened to the escutcheon plate 2 by means of screws 46. A semi-circularly shaped actuating member 47 for actuating the contact springs comprises a pivoted body or cam and pivotally supported in the frame 45 by means of the pivot pin 48. Mounted upon the lower end of the cam 47 are rollers 49 and 50 of suitable insulating material, and rotatably secured thereto and positioned between the free ends of the pair of springs 51 and 51' of the listening spring group LS and the free ends of the pair of springs 52 and 52' of the ringing spring group RS. The listening spring group LS and the ringing spring group RS are insulatingly mounted upon the frame 45 by means of insulated screws 53.

20 In keys of the above type in which a two-way rocking key is provided in addition to the usual four-party ringing keys, indicating means are adapted to indicate which one of the key plungers was last operated, 25 but no indication is given when the rocking key was last actuated for ringing purposes, and to provide a means therefor an arm 54 is secured to the cam 47 by means of the screw 55 and normally rests 30 in the position as clearly illustrated in Figs. 1 and 13. The latch plate 25 is provided on the side opposite that of the projection 32 with a downwardly extending ear 56 angularly displaced inwardly relative to the face 35 of the latch plate 25, and this ear 56 is operatively associated with the nose 57 of the arm 54 and engaged by the said nose 57 to move the plate 25 outwardly when the lever L of the rocking key is moved to the left 40 into ringing position to unlatch any key plunger that may be in an indicating position, as will be more fully hereinafter described. The latch plate 25 is held in its position by means of a coil spring 58, which 45 spring 58 has one of its ends secured to the plate 25 and its other end secured to a pin 59, which pin 59 is suitably secured to the leg 4 of the frame 3.

50 In the operation of any one of the keys the movement of the parts will be as follows: Assuming that the key starts from its normal position, the first movement thereof will bring the cam surface 61 of the angular projection 24 of the key plunger P into engagement with the edge 62 of the member 30 of the latch plate 25, and the continued downward movement of the key plunger P forces the said latch plate 25 outwardly against the action of the spring 58. The roller 22 secured to the body portion 16 of the plunger P, when moved into engagement with the spring 13, forces it out of engagement with a spring 14 and into engagement with the spring 12. The 55 downward pressure on the key plunger rod

is continued to force the said key plunger into its fully depressed position. After the apex 63 of the projection 24 of the key plunger passes the edge 64 of the member 30, the cam face 61 of the projection 24 now engages the face 165 of the inwardly projecting member 31 of the latch plate 25 and further forces the plate 25 outwardly until the plunger is in the position as illustrated in Fig. 8. The movement of the plate 25 forces the member 33 secured to the arm 32 into engagement with the spring 36, moving the end springs 36, 37, 38, 39, 40 and 41 to their alternate positions. A coiled actuating spring 65 is provided which surrounds the lower portion 17 of the key plunger P, bearing at its opposite ends against the shoulder 66 of the plunger P and the angular portion 21 of the plate member 20. This coiled spring 65 is compressed when the key plunger P is depressed, and when the pressure of the finger is released the coil spring 65 moves the key plunger upward until the apex 63 of the projection 24 of the plunger P engages the bottom face 68 of the member 30, thus holding the key plunger in its indicating position, as illustrated in Fig. 9. As the key moves upward, the plate 25 moves inwardly due to the tension of the spring 58, causing the member 33 to disengage the spring 36 and allow the springs 36, 37, etc., to assume their normal position. Thus, it may be seen that each time that a key plunger P is depressed, the end spring group ES assumes its alternate position. Assuming that another key plunger P is depressed, the projection 24 of the said key plunger engages the member 30, forcing the plate 25 outwardly, as already described, and when the face 68 of the member 30 passes the apex 63 of the projection 24 of the key plunger P that is in indicating position, it is released and the coil spring 65 forces the key plunger P from its indicating position to its normal inoperative position.

Assuming that a key plunger P is in its indicating position and the lever L of the rocking key is moved to the left to operate its ringing contacts. The movement of the lever L rotates the cam 47 and as the arm 54 is secured to the cam 47 the said arm is moved in a downward direction, causing the nose 57 of the arm 54 to engage the angular face 70 of the ear 56 of the plate 25. The continued movement of the lever L causes the arm 54 to force the plate 25 outwardly, causing the face 68 of the member 30 to disengage the apex 63 of the projection 24 of the key plunger P that is in indicating position. This releases the locked key plunger P that is in an indicating position, and the coil spring 65 restores the said key plunger to normal. When the key lever L is moved to the right into listening position,

the arm 54 is moved in an upward direction and does not affect the latch plate 25 or any key plunger that may be in an indicating position.

5 Key caps or buttons 71 of hard rubber or other suitable material are provided and are secured to the portion 15 of the key plunger P by means of screws 72 which pass through suitable openings in the caps 71 and have 10 screw-threaded engagement with suitable tapped openings in the upper portions 15 of the key plunger P. Circular disks 73 of felt are slipped over the portions 15 of the key plungers P, and circular disks 74 of metal are placed between felt disks 73 and the shoulder 75 formed by the portion 15 and the body portion 16 of the said plungers, and these felt disks 73 and disks 74 act as cushions when any one of the plungers are 15 restored to normal by the action of the spring 65.

In Fig. 1 I have shown the plunger X controlling a differently constructed set of springs than the other plungers control. 20 When the plunger X is operated to its indicating position, it does not affect its springs Y. These springs are not affected until the plunger X is moved to its fully operated position, at which time the common end springs are operated, as well as the springs Y. I have shown the plunger X controlling this modified set of springs because certain types of ringing circuits require such a set of springs.

25 From the foregoing it will be apparent that my device is so constructed that when a plunger P is operated a previously depressed plunger will be released before the plunger being depressed has moved far enough to be latched in its indicating position, and that when the plunger is farther depressed the latch plate is moved outwardly farther and the common end springs are operated.

30 While I have illustrated and described a particular key structure and spring arrangement, I do not wish to be limited to the exact form, as many changes and modifications may be made without departing from the scope of the invention, and I aim to cover all such changes and modifications as come within the spirit and scope of the appended claims.

35 What I claim as new and desire to secure by United States Letters Patent, is:

1. A device of the character described including a frame, a plurality of reciprocating plungers supported by said frame, said plungers having a cross-section to prevent their rotation relative to said frame, an integrally formed ear for each of said plungers, a latch plate pivotally supported by said frame, and integrally formed ears for said latch plate for cooperating with the ears of said plungers in such a manner that

when one plunger is depressed, the ear of said plunger engages one of the ears of said latch plate to release any previously operated plunger to its normal position and the depressed plunger is held in an indicating position by the ear of said plunger engaging one of the other ears of said latch plate.

2. A device of the character described including a frame, a plurality of reciprocating plungers supported by said frame, an integrally formed ear for each of said plungers, said plungers having a cross-section to prevent their rotation relative to said frame, a latch plate pivotally supported by said frame and integrally formed ears for said latch plate for cooperation with said ears of said plungers in such a manner that when one plunger is depressed the ear of said plunger engages one of the ears of the said latch plate to release any previously operated plunger to its normal position and the depressed plunger is held in an indicating position by the ear of said plunger engaging one of the other ears of said latch plate, and spring contacts controlled by each of said plungers.

3. A device of the character described including a frame, a plurality of reciprocating plungers carried by said frame, each of said plungers having a normal, an indicating and a fully operated position, said plungers having a cross-section such as to prevent their rotation relative to the frame, an integrally formed ear for each of said plungers, a latch plate pivotally supported by said switch frame, pairs of integrally formed ears for said latch plate, each pair of said ears cooperating with the ears on said plungers, the projecting ears on said latch plate cooperating with the projecting ears on said plungers in such a manner that when one plunger is depressed from its normal to its indicating position, the ear of said plunger engages an ear of a pair on said latch plate which are associated with said depressed plunger so that any previously depressed plunger will be released to its normal position, and springs operable by said latch plate when the plunger is further depressed from its indicating to its fully operated position.

4. A device of the character described including a frame, a plurality of one-piece reciprocating plungers carried by said frame, each of said plungers having a normal, an indicating and a fully operated position, said plungers having a cross-section such as to prevent their rotation relative to the frame, an integrally formed ear for each of said plungers, a latch plate pivotally supported by said switch frame, pairs of integrally formed ears for said latch plate, each of said pairs of ears being associated with a key plunger and cooperating with the ears on said plungers, the pairs of

projecting ears on said latch plate cooperating with the projecting ears on said plungers in such a manner that when one plunger is depressed from its normal to its indicating position the ear of said depressed plunger engages an ear of a pair on said latch plate, which are associated with said depressed plunger so that any previously depressed plunger will be released to its normal position, and a projecting ear for said latch plate cooperating with said frame for limiting the movement of said latch plate in one direction.

5. A device of the character described including a frame, a plurality of reciprocating plungers carried by said frame, each of said plungers having a normal, an indicating and a fully operated position, said plungers having a cross-section such as to prevent their rotation relative to the frame, an integrally formed ear for each of said plungers, a latch plate pivotally supported by said switch frame, integrally formed ears for said latch plate for cooperation with the ears on said plungers, the projecting ears on said latch plate cooperating with the projecting ears on said plungers in such a manner that when one plunger is depressed from its normal to its indicating position any previously depressed plunger will be released to its normal position, a projecting ear for said latch plate for limiting the movement of said latch plate in one direction, and a locking key associated with said reciprocating plungers and adapted when moved in one direction to cooperate with said limiting ear to release any plunger that is in an off-normal position.

40 6. A device of the character described including a supporting frame, a plurality of reciprocating plungers supported by said frame, rectangular slots in said frame in which said plungers are mounted and held against rotary movement relative to the mounting frame, a spring supporting plate secured to said frame independently and free from said plungers, and a removable unit consisting of a plurality of switch springs for each of said plungers attached to 45 said spring supporting plate.

55 said spring supporting plate.

7. A device of the character described including a supporting frame, a plurality of reciprocating plungers supported by said frame, rectangular slots in said frame in which said plungers are mounted and held against rotary movement relative to the mounting frame, a spring supporting plate secured to said frame independently and free from said plungers, and a mounting member to which switch springs are attached forming a unitary structure for each of said plungers, said unitary structure being adapted to be attached to said spring supporting plate in such a manner that it

60 may be readily removed and the entire

65

spring combination controllable by any plunger changed without dismantling the springs of a set.

8. A device of the character described including a supporting frame, a plurality of reciprocating plungers supported by said frame, each provided with an integrally formed ear, rectangular slots in said frame in which said plungers are mounted and held against rotary movement relative to the mounting frame, a spring supporting plate secured to said frame, a mounting member to which switch springs are attached forming a unitary structure for each of said plungers, said unitary structure being adapted to be attached to said spring supporting plate in such a manner that it may be readily removed and the entire spring combination controllable by any plunger changed without dismantling the springs of a set, and a pivoted latch plate supported by said frame and provided with pairs of integrally formed ears, a pair of said ears being associated with each plunger and cooperating with said plungers in such a manner that when one of said plungers is depressed, said one plunger will be held in its depressed position until another one of said plungers is depressed whereby said previously depressed plunger will restore to its normal position and said other depressed plunger will be held in its indicating position by its ear engaging the ear of a pair associated with said other depressed plunger. 70 75 80 85 90 95

9. A device of the character described including a supporting frame, a plurality of reciprocating plungers supported by said frame, each provided with an integrally formed ear, rectangular slots in said frame in which said plungers are mounted and held against rotary movement relative to the mounting frame, a spring supporting plate secured to said frame, a mounting member to which switch springs are attached forming a unitary structure for each of said plungers, said unitary structure being adapted to be attached to said spring supporting plate in such a manner that it may be readily removed and the entire spring combination controllable by any plunger changed without dismantling the springs of a set, a pivoted latch plate supported by said frame and provided with pairs of integrally formed ears, a pair of said ears being associated with each plunger and cooperating with said plungers in such a manner that when one of said plungers is depressed, said one plunger will be held in its depressed position until another one of said plungers is depressed whereby said previously depressed plunger will restore to its normal position and said other depressed plunger will be held in its indicating position by its ear engaging the ear of a pair associated with said other depressed plun- 100

ger, and a projecting ear for said latch plate which cooperates with said mounting frame to limit the movement of said latch plate in one direction.

- 5 10. A device of the character described including a supporting frame, a plurality of reciprocating plungers supported by said frame, rectangular slots in said frame in which said plungers are mounted and held 10 against rotary movement relative to the mounting frame, a spring supporting plate secured to said frame, a mounting member to which switch springs are attached forming a unitary structure for each of said plungers, 15 said unitary structure being adapted to be attached to said spring supporting plate in such a manner that it may be readily removed and the entire spring combination controllable by any plunger changed without 20 dismantling the springs of a set, a pivoted latch plate supported by said frame cooperating with said plungers in such a manner that when one of said plungers is depressed any previously depressed plunger 25 will restore to its normal position, a projecting ear for said latch plate which cooperates with said mounting frame to limit the movement of said latch plate in one direction, and a rocking key associated with 30 said mounting frame and plungers in such a manner that when the rocking key is moved in one direction it cooperates with said limiting member in a manner to release any plunger that is in an off-normal position. 35

11. A device of the character described including a frame, a plurality of reciprocating plungers supported by said frame, each being provided with an integrally 40 formed ear, said plungers having a cross-section to prevent their rotation relative to said frame, pairs of integrally formed ears for said latch plate for cooperation with the ears of said plungers in such a manner 45 that when one plunger is depressed the ear of said plunger engages one of the ears of a pair on said latch plate associated with said plunger so that any previously operated plunger will be released to its normal 50 position and the depressed plunger held in an indicating position by the ear on said depressed plunger engaging the other ear of the pair associated with said depressed plunger, spring contacts controlled by each 55 of said plungers, and springs supported by said frame adapted to be operated each time a plunger is moved from its indicating to its fully operated position.

12. A device of the character described including a frame, a plurality of reciprocating plungers supported by said frame, said plungers having a cross-section to prevent their rotation relative to said frame, ears for said plungers, integrally formed ears for said latch plate for cooperation with the ears of said plungers in such a manner that when one plunger is depressed any previously operated plunger will be released to its normal position and the depressed plunger held in an indicating position, spring contacts controlled by each of said plungers, springs supported by said frame adapted to be operated each time a plunger is moved from its indicating to its fully operated position, and a rocking key 75 associated with said device and cooperating therewith in such a manner that when the rocking key is operated a plunger is released.

13. A device of the character described including a frame, a plurality of reciprocating plungers carried by said frame, each of said plungers having a normal, an indicating and a fully operated position, said plungers having a cross-section such as to prevent their rotation relative to the frame, an integrally formed ear for each of said plungers, a latch plate pivotally supported by said switch frame, pairs of integrally formed ears for said latch plate, a pair of 90 said ears being associated with an ear on each said plunger and adapted for cooperation with the ears on said plungers, other projecting means for said latch plate, the projecting ears on said latch plate cooperating with the projecting ears on said plungers in such a manner that when one plunger is depressed from its normal to its indicating position the ear of said plunger engages one of the ears of a pair associated with said depressed plunger so that any previously depressed plunger will be released to its normal position, and springs operable by said latch plate when the plunger is further depressed from its indicating 105 to its fully operated position, the ear on said plunger cooperating with the projecting means on said plate in such a manner when the plunger is moved from its indicating to its fully depressed position that the latch plate is caused to move to operate a set of springs common to the device.

Signed by me at Chicago, in the county of Cook and State of Illinois, this 9th day of October, 1920.

ERNEST A. BOHLMAN.
